JULIUS E. PATTERSON AND FELIX E. DUNN, OF KLAMATH FALLS, OREGON, ASSIGNEES,
BY MESNE ASSIGNMENTS, TO DUNN-PATTERSON COMPANY, A CORPORATION OF
OREGON.

AUTOMATIC LAND LEVELER AND GRADER.

Application filed May 23, 1922. Serial No. 563,019.

To all whom it may concern:

Be it known that we, JULIUS E. PATTERSON and FELIX E. DUNN, citizens of the United States, residing at Klamath Falls, in the county of Klamath and State of Oregon, have invented new and useful Improvements in Automatic Land Levelers and Graders, of which the following is a specification.

10 This invention relates to improvements in apparatus for leveling and grading industrial and agricultural land, roadways, and the like and resides in the provision of apparatus by means of which such operations may be more economically, effectively and expeditiously carried out.

An object of the invention is to provide vehicular apparatus of the character described which during the continuous progress thereof and at the will of the operator, by manipulation of a single control element, the apparatus may be caused to pick up or scoop, to convey and to dump dirt or other material.

25 Another object of the invention is to provide apparatus of the character described wherein the scoop forming a part of the invention may be, at will, moved into and maintained in any one of its various positions by an easy manipulation of a single control element during and without interrupting the progress of the vehicle forming a part of the apparatus.

30 A further object is to provide in apparatus of the character described means with which the depth of the scooping action may be regulated as desired and the dumping operation may likewise be regulated so that either a gradual dumping or quick dumping action may be effected.

35 Another object is to generally improve and simplify the construction and operation, reduce the cost of manufacture and render more generally useful grading and leveling apparatus of the type described.

40 A further object is to provide apparatus of the character described in which the parts and elements of the apparatus will be automatically returned to normal position.

45 Another object is to provide in apparatus of the character described automatic and semi-automatic control and operating mechanism which will facilitate the work of scooping, conveying and dumping dirt or

other material particularly in that it will 55 simplify and render more efficacious the operation of the apparatus.

The invention possesses other advantages and features some of which, with the foregoing will be set forth at length in the following description where we shall outline in full that form of the invention which we have selected for illustration in the drawings accompanying and forming a part of the present specification. In said drawings 60 we have shown one form of the construction of our invention, but it is to be understood that we do not limit ourselves to such form since the invention as expressed in the claims may be embodied in a plurality of 65 forms.

Referring to the drawings:

Fig. 1 represents a top plan view of the apparatus of our invention.

Fig. 2 represents a longitudinal sectional 75 view showing the mechanism in side elevation in full lines as after a dumping operation.

Fig. 3 represents a view in elevation of the clutch mechanism.

Fig. 4 represents a side elevation partly in section of the clutch mechanism showing part of the main operating mechanism.

Fig. 5 represents a sectional view of a detail of construction in the main operating 85 mechanism which is shown in elevation at the left hand side in Fig. 4.

Fig. 6 represents a cross sectional view through the tongue of the vehicle showing the manner of mounting the slide member 90 thereon.

Fig. 7 represents a semi-diagrammatic view of the apparatus as when in position for scooping or loading.

Fig. 8 represents a semi-diagrammatic 95 view showing the mechanism when the scoop is in dumping position.

Referring to the embodiment of the invention illustrated in the accompanying drawings, 1 designates a frame carrying an axle 2 upon which vehicle wheels 3 are loosely mounted. These wheels are adapted to be locked so as to rotate the axle through the use of clutch mechanisms 4 and 5, which mechanisms will be later more fully described. A tongue 6 extends forwardly from one end of the frame and is adapted 100 for connection with a tractor, not shown. 105

When the apparatus of my invention is to be horse drawn, the tongue or frame may be associated with an additional wheeled truck, which latter, it is not thought necessary to illustrate. At the rear of the frame a driver's or operator's seat 7 is mounted in any suitable manner.

Supported from the axle 2 is a scoop or pan 8 such as is ordinarily employed in graders and land levelers, said scoop comprising a bottom wall 9, rear wall 10 and side walls 11, arranged whereby the front end and upper side of the scoop are open. Rigidly fixed to the side walls 11 and curving upwardly and rearwardly therefrom are slotted plates 12 in which certain edges of the slots are provided with teeth so as to serve as racks 13. The axle 2 extends through the slots in the plates and has mounted thereon pinions 14 which mesh with the racks 13. The hub portions 15 of the pinions are engaged by flanges 16 provided on the plates 12. The pinions are keyed as at 17 to the shaft and are either integral 25 with or rigidly carried by a combined pulley and detent wheel members 18. Each of these members 18 is constructed so as to provide a pulley 19 joined with a detent wheel portion 20, there being a detent recess or 30 notch 21 formed in the periphery of the portion 20. By this arrangement it will be seen that when the clutches 4 and 5 are operated to lock the vehicle wheels to the axle, the axle will be rotated and the pinions 14 35 will rotate in such manner as to cause the racks to be moved forwardly and downwardly (due to the curve of the racks) whereby the scoop 8 will be moved into scooping or loading position. The extent of 40 downward movement of the pan may be regulated as desired and the depth of the scooping operation may be likewise controlled, both, as will later be more fully described.

To provide for moving of the scoop so 45 that the load may be dumped, means is employed for automatically locking the detent wheels 20 with the plates 12, after a scooping or loading operation has been completed, whereby the scoop will be moved upwardly 50 and rearwardly into dumping position due to the locking of the teeth of the pinions with the teeth of the rack. This may be carried out without interrupting the progress of the vehicle and may be effected at 55 the will of the operator. The means above described may comprise as shown, detent members 22 pivoted intermediate of their ends as at 23, to the plates 12, in such manner that the lower ends of the detent members, which ends are bent right angularly 60 as at 24, may be caused to extend into the notches 21 in the detent wheels 20. Retractable springs 25 are attached at certain ends as at 26 to the side walls 11 of the 65 scoop and at their other ends are connected

as at 27 with the detent members 22, at points on the latter such that the ends 24 of the detents will at all times be urged towards the peripheries of the detent wheels 20. Pivoted to the frame 1 as at 28 are trip members 29 which are adapted to rest upon the upper ends of the detent members 22 and to also engage said members 22 so as to limit their movement. These trip members 29 are limited in their downward movement by stops 30 carried on the frame 1 and are so positioned relative to the members 22 that after a scooping operation and upon movement of the scoop into position shown in Fig. 2, they will engage the rear sides of the detent members so as to hold the detent members free from engagement with the notches 21 and permit of movement of the scoop downwardly relative to the axle instead of arcuately and bodily and with the axle. This movement of the scoop will cause the detent members to move downwardly so that their lower ends will move past the trip members and the springs 25 will then move the detents so that the ends 24 will engage with the peripheries of the detent wheels 20 and thereby be in position to extend into the notches when the latter are moved into proper position. The movement of the notches into proper position to receive the detent members will take place immediately when, after a loading or scooping operation, the pan is lifted into normal position clear of the ground as shown in Fig. 2. At this time the trips 29 will not interfere with the holding action of the detent members 22 and as the vehicle continues in its movement the operator may, at will, manipulate the clutches 4 and 5 so as to turn the axle 2 and cause movement of the scoop such that it will dump its load.

There is provided a single operating element in the form of a pedal or lever, the manipulation of which, to actuate the clutches, will permit of the operation of the pan to scoop, convey and dump material as desired without arresting the progress of the vehicle in any manner, this may comprise a lever 31 which is fixed at its lower end to a shaft 32 which shaft extends transversely of and is journaled in suitable bearings 33 on the frame 1. At a point intermediate of its ends the lever has a foot piece or treadle 34 attached thereto so that it may be operated as a pedal, but said lever extends above the foot piece so that it may be manipulated as a hand lever also, if desired. Fixed to and depending from the shaft 32 are arms 34 to which are connected rods 35 leading to the clutches 4 and 5. Each clutch is identical as to construction and includes a shaft carried actuating means generally designated 36, operating the clutch elements proper. The shaft carried actuating means comprises a toothed

collar 37 fixed to the frame 1 and through which the axle loosely extends. The teeth on the collar are disposed on the outer side face thereof and are adapted to cooperate with similar teeth 38 on a similar collar 39. The collar 39 is loosely mounted on the axle 2 and is provided with a rigid depending arm 40, the lower end of which is pivoted to one of the rods 35.

10 The rotatable collar 39 is provided upon its outer side face with a cam surface 41 against which a roller 42 is adapted to engage. The roller 42 is mounted upon and extends at right angles to a circular disc 43, which latter is loosely mounted upon the axle 2 and is adapted to be moved longitudinally on the axle. The disc is preferably concave on its inner side and adjacent its outer periphery carries a band of friction material 44 which is adapted to bear upon a clutch drum 45 fixed to the hub of the adjacent vehicle wheel. Keyed to the axle 2 as at 46, is an arm 47 to the outer end of which certain ends of clutch ring segments 48 and 49 are pivoted. These members are adapted to engage the inner face of the flange 50 of the drum 45 and by frictional engagement, lock with said drum such that the rotation of the vehicle wheels will cause the axle 2 to be rotated. The other ends of the segments 48 and 49 are inwardly offset and the segment 48 is pivoted as at 51 to the outer end of a toggle lever 52. The offset end of the segment 49 is pivoted as at 53 to the lever 52 at a point between the ends of said lever. The inner end of the lever 52 is rounded and enlarged as at 54 so that it will loosely engage in a socket 55 formed in an offset portion 56 of the disc 43. Normally the drums 50 rotate with the wheels without imparting rotary movement to the axle. When the lever 52 is moved forwardly a pull is communicated to the rods 35 such that the collars 39 will be turned on the axle 2 and due to the arrangement of the teeth on the collars 37 and 39, the collars 39 will move longitudinally towards the rollers 42 as well as be given a rotary movement in the direction of travel of the vehicle. This will dispose the cam surface 41 such that the rollers 42 will be forced inwardly and will cause the disc 43 to press against the drum 45. The frictional engagement of the band 44 with the drum 45 will cause the disc 43 to turn slightly relative to the axle and due to such rotation the toggle lever 52 will be rocked and will cause the clutch ring segments 48 and 49 to frictionally engage with the flange 50 of the clutch drum 45. This will through the segments 48 and 49 and the arm 47 transmit rotation to the axle 2. Upon rotation of the axle, the scoop operating mechanism previously described will be actuated. The clutches do not, however, remain "clutched" but will

declutch after a predetermined rotation of the vehicle wheels, unless the clutch lever is given further operative movement and the collars 39 are further shifted on the axle. Since the collars 39 do not rotate with the axle and the rollers 42 each transmit an actuating force to the clutches, which latter rotate with the vehicle wheels, when the clutches are in operation, said rollers will be moved away from the pressure effecting portions of the cam surfaces 41 such that the actuating pressure imparted from the cams through the rollers is diminished and the clutch mechanisms will be declutched. The clutch mechanisms are, therefore, considered as progressive, since the maintaining of the clutches in "clutched" position such that rotation will be imparted to the axle, is dependent upon movement of the lever 31 and collars 39. This operation will be later more fully described.

There is provided means for returning the scoop and associated mechanism to normal position after the dumping operation and upon declutching the clutches, which means is automatic in its operation and will herein-after be described. A slide member 57 operates between spaced bars 58 constituting the tongue 6. The slide is provided with flanges 59 and 60 to engage the upper and lower edges of the bars 58 respectively, to hold the slide in place. From the flanges 60 the slide extends downwardly, providing ears 61 extending through which is a pin 62. Mounted upon the projecting ends of the pin and held in place by cotter pins 63 are eyes 64 on the outer ends of draw bars 65. The other ends of the draw bars are pivoted as at 66 to the sides 11 of the scoop adjacent the forward end of the scoop. Mounted in a slotted plate 67 fastened to the tongue in front of the slide member is a pin 68 to opposite ends of which pin are attached ears 69. To the ears are secured certain ends of heavy retractile springs 70. To the other ends of the springs 70, cables 71 are attached and said cables are secured to and adapted to be wound upon the pulley members 19. The slide member is adapted to engage the ears 69 just before completing its forward movement, for the purpose of cushioning the movement thereof when the parts are returned to normal position so as to avoid slamming of the parts.

There is provided means for locking and releasing the slide member, depending upon the position of the scoop 8, which means will release the slide member when the scoop is to be moved but lock it when the scoop is disposed in a scooping or loading position. As shown, this means may comprise a locking member 72 which is pivoted as at 73 at one end to a suitable mounting 74 on the tongue 6. The other end of the locking member is adapted to engage a lock-

ing shoulder 75 provided on the upper side of the slide member 57. The movement of the locking member is automatically controlled by a plunger 76 slidably mounted in 5 a sleeve 77 supported by the tongue 6. One end of the plunger engages under the locking member and the other end is provided with an enlarged rounded head 78 which head is adapted to be engaged by an abutment member 79, supported by the draw bars 65. When the scoop is in normal or loaded position as shown in Fig. 2, the abutment 79 engages the head 78 of the plunger 76 and holds the plunger in such engagement with the locking member 72 that the latter is held clear of the shoulder 75 on the slide 57. However, when the scoop 8 is lowered into scooping or loading position, the bars 65 are likewise lowered and the 20 abutment member moves away from the plunger so that the plunger recedes and allows the locking member to move into locking position. This locks the slide member against inward sliding movement and 25 through the draw bars 65 prevents rearward or upward movement of the scoop when the latter is in scooping or loading position.

There may be provided a guard and trap 30 member 80 attached to each side wall 11 of the scoop 8 and arranged so as to protect the pinions 14 and racks 13 against having dirt accumulating or being thrown thereon. These members 80 are provided with outlet 35 openings 81 arranged so that any dirt collect thereon will discharge along the outer sides of the scoop.

Operation.

Assuming that the machine is ready for 40 operation and the parts are arranged as shown in Fig. 2, (full lines) with the scoop in lifted position and empty, the vehicle is moved in the desired direction across the surface of the ground to be treated. In order to 45 scoop up the ground or material to be loaded into the scoop, the operator by pressing on the treadle 34 or otherwise moving the lever 31 forwardly, communicates a pull to the rods 35 and rotates the collars 39 so that the collars are shifted arcuately and are moved bodily outwardly at the same time. This will cause the cam surfaces 41 to press upon the rollers 42 and transmit an outward- 50 ly actuating pressure to the discs 43. When the discs 43 are forced against the drums 45 the frictional engagement between these parts causes the discs to be turned relative to the axle and the treadle levers 52 to be 55 rocked so as to cause the segments 48 and 49 to lock with the clutch drums 45. Since the clutch segments are fastened to the arm 47 which is keyed to the axle 2, the axle 2 will be rotated correspondingly with the 60 vehicle wheels and since the detents, as

shown in full lines in Fig. 2, are free of holding position with relation to the detent wheels 20, rotation of the axle will cause the pinions 14 to actuate the racks 13 such that the scoop 8 will be lowered downwardly and forwardly (due to the shape of the racks) until the forward edge of the scoop is in position shown in Fig. 7, and will have a tendency to scoop up the ground or other material. By holding the clutch lever 31 in a fixed position the downward movement of the scoop will cease and be maintained coincident with the cessation of the forward movement of the clutch member but the arrangement of the parts is such that no backward or upward movement of the scoop will take place. The extent of the downward movement of the scoop and consequently the degree of the extensions of the forward edge thereof into the material or ground 75 may be varied as desired by continuing or stopping the forward movement of the clutch lever. When the scoop lowers into scooping position the plunger 76 is lowered and permits the locking member 72 to engage and lock the slide 57. This locking of the slide will prevent movement of the draw bar 65 and will hold the scoop 8 against backward and upward movement.

After the scoop 8 has been moved sufficiently to become loaded, the operator releases the clutch and the spring 70 which have been expanded, due to the winding of the cable 71 upon the pulleys 19, will contact with sufficient force to rotate the members 18 and pinions thereon in the reverse direction. This will operate through the racks 13 so as to lift the loaded scoop into position shown in Fig. 2, clear of the ground. Movement of the scoop into "up" 95 position lifts the draw bars such that the abutment member 79 engages the plunger 76 and causes the locking member 72 to be lifted upwardly clear of the locking shoulder 75 and thereby releases the slide member 57. When the scoop is raised after being loaded, the upper ends of the detents 22 are so disposed that they will engage under the trip members 29. In this 100 way the trips 29 do not interfere with the movement of the ends of the detent members into the notches 21 and this movement into the notches takes place automatically, due to the action of the springs 25, when the scoop is lifted into "up" position.

The load, thus held in the scoop, may be carried forwardly to the desired place or dumped immediately as desired, depending upon the grading or leveling operation to be carried out. When the operator desires to dump the load the clutch lever is pushed forwardly so as to cause the clutches to lock the wheels to the axle and the axle to rotate. Since the detent members hold the plates 12 against movement relative to the 115 120 125 130 135 140

axle at this time said members 12 with the scoop supported thereby, are moved bodily in such manner that the back of the scoop is moved upwardly in an arcuate path and the load of material will drop from the scoop through the open front end thereof. This movement of the scoop may be varied in order that the load may be dropped gradually or dumped quickly, by varying the forward movement of the lever 31. Likewise the scoop may be held in position to gradually or freely dump its load, by holding the lever 31 in a certain position. The reason for this action will be apparent since when after a shifting of the collars 39 to dispose the cam surface 41 in a certain position and to effect a clutching of the clutch mechanisms, as the vehicle continues in its travel, the rollers 42 through 20 which the actuating pressure from the collars is transmitted are carried with the wheels in the direction of the decreasing surface of the cam. When the actuating pressure is relieved, the rollers 42 move relative to the cam surfaces in this manner, until the frictional engagement of the discs 43 with the drums 45 is reduced to such extent that no rotary movement will be imparted to the discs 43. Upon cessation of movement of the disc 43 the clutching force applied by the discs to the segments 48 and 49 is stopped and the clutch mechanisms automatically "declutch". The arrangement of the rollers and cams with their mechanisms is such, however, that sufficient resistance is set up to hold the scoop in a position to which it has been moved, as previously described. It follows therefore, that in order to provide for continuous movement of the scoop, either when moving it into scooping position or into dumping position, it is necessary that the scoop lever and collars 39 be moved continuously during the time of the desired continuous movement of the scoop. Otherwise the actuating pressure imparted from the shiftable collars through the rollers to the discs 43 would not be maintained because the rollers 42 move away from the pressure effecting portions of the cam surfaces with the travel of the vehicle wheels.

When the load has been dumped as desired, by releasing the clutch pedal and declutching the clutch mechanisms, the springs 55 which have again been stretched, will contract and through the pulley 71 actuate the mechanism by reversing the movement of the axle in such manner that the scoop with other parts will be returned to normal position as shown in Fig. 2. As the scoop and other parts are returned to normal position the slide member 57 will contact with the pin 68 to which the springs 70 are attached in such manner that before the end 60 of the movement of the slide member the

springs will be stretched and cushion the shock or jar which might be occasioned otherwise.

We claim:

1. Land leveling and grading apparatus comprising a frame, wheels supporting the frame, an axle rotatable in the frame and upon which the wheels are loosely mounted, clutch mechanisms for locking the wheels to and causing rotation of the axle, means for operating the clutch means, a scoop and means of operative connection between the scoop and axle providing for movement of the scoop into scooping, load conveying and load dumping positions when the clutches are operated to cause rotation of the axle. 70

2. Land leveling and grading apparatus comprising a frame, wheels supporting the frame, an axle rotatable in the frame and upon which said wheels are loosely mounted, a scoop movable with relation to the frame into scooping, load conveying and load dumping positions, clutch means for locking the wheels to the axle and causing rotation of the axle, means for operating the clutch means, means which when the scoop is maintained in position clear of the ground will automatically move the scoop into scooping position when the axle is rotated, means which upon cessation of rotation of the axle will automatically lift the scoop into load conveying position and means which after said movement of the scoop into load conveying position and the axle is again rotated will automatically move the scoop into position to dump the load therefrom. 80

3. Land leveling and grading apparatus comprising a frame, wheels supporting the frame, an axle rotatable in the frame and upon which said wheels are loosely mounted, a scoop movable with relation to the frame into scooping, load conveying and load dumping positions, clutch means for locking the wheels to the axle and causing rotation of the axle, means for operating the clutch means, means which when the scoop is maintained in position clear of the ground will automatically move the scoop into scooping position when the axle is rotated, means which when the clutch is detached will automatically lift the scoop into load conveying position, means which after said movement of the scoop into load conveying position and the axle is again rotated will automatically move the scoop into position to dump the load therefrom and means which after the scoop is moved into dumping position will upon release of the clutch mechanisms automatically move the scoop into normal position clear of the ground. 90

4. Land leveling and grading apparatus comprising a frame, wheels supporting the frame, an axle rotatable in the frame and upon which said wheels are loosely mounted, clutch means for locking the wheels to and

rotating the axle a scoop operatively associated with the axle and adapted to be moved from a position clear of the ground into scooping position, then into load conveying 5 position and then into dumping position, a rack carried by the scoop, a pinion fixed to the axle and engaging the rack, said rack and scoop being normally movable with relation to the axle and means operating automatically when the scoop is moved from 10 normal position into scooping position for locking the rack and scoop against movement relative to and causing movement of the scoop with the axle whereby the scoop 15 will be tilted and the load therein will be dumped.

5. Land leveling and grading apparatus comprising a frame, an axle rotatable on the frame, wheels rotatable on the axle, clutch 20 means for locking said wheels to and causing rotation of the axle, a scoop and means which when the wheels are continuously moved and the clutch is operated to lock the wheels with the axle will cause the scoop to 25 be moved into scooping position, means which upon release of the clutch means after a scooping operation will automatically move the scoop into load conveying position, means which when the scoop moved into load 30 conveying position and upon again locking the wheels to the axle will automatically move the scoop into load dumping position and means which upon a declutching action of 35 the clutch mechanisms after movement of the scoop into dumping position will automatically move the scoop into position clear of the ground.

6. Land leveling and grading apparatus comprising a frame, an axle rotatable on the 40 frame, wheels supporting said axle and rotatable thereon, clutch means for locking said wheels to and causing rotation of the axle upon movement of the wheels, a scoop, a rack bar on the scoop, a pinion fixed to the 45 axle and engaging the rack bar, means which after movement of the scoop into scooping position and upon release of the clutch mechanisms will automatically lift the scoop clear of the scooping position and into load 50 conveying position and means which after movement of the scoop into load conveying position and upon locking of the wheels with the axle will automatically tilt the scoop so that the load will be dumped when the axle 55 is rotated.

7. In land leveling and grading apparatus comprising a frame, an axle rotatable upon the frame, wheels supporting said axle and rotatable freely thereon, a scoop operatively 60 associated with the frame and axle, means which when the axle is turned will move the scoop into scooping, conveying and unloading positions and means for controlling the operation of said last named means comprising a collar fixed to the frame and sur-

rounding the axle, another collar loosely surrounding the axle, said collars having cam surfaces on opposite faces engaging with one another, means adapted to be actuated by the operator of the apparatus for turning the 70 loosely mounted collar and causing it to be shifted longitudinally on the axle, a clutch drum fixed to the wheel and loosely surrounding the axle, a clutch member fixed to the axle and adapted to be moved into and out of frictional engagement with the clutch drum, a friction member on the axle and adapted to be moved into and out of frictional engagement with the drum, means carried by the frictional member arranged 75 to be engaged by the said loosely mounted collar when the latter is shifted longitudinally, to force the friction member into frictional engagement with the drum and means which upon engagement of said friction member with the drum will move the second named clutch member in frictional engagement with said drum.

8. In land leveling and grading apparatus comprising a frame, an axle rotatable upon 90 the frame, wheels supporting said axle and rotatable freely thereon, a scoop operatively associated with the frame and axle, means which when the axle is turned will move the scoop into scooping, conveying and unloading 95 positions and means for controlling the operation of said last named means comprising a collar fixed to the frame and surrounding the axle, another collar loosely surrounding the axle, said collars having cam surfaces on opposite faces engaging with one another, means adapted to be actuated by the operator of the apparatus for turning the loosely mounted collar and causing it to be shifted longitudinally on 100 the axle, a clutch drum fixed to the wheel and loosely surrounding the axle, a clutch member fixed to the axle and adapted to be moved into and out of frictional engagement with the clutch drum, a friction member on the axle and adapted to be moved into and out of frictional engagement with the drum, means carried by the friction member arranged to be engaged by the said 105 loosely mounted collar when the latter is shifted longitudinally to force the friction member into frictional engagement with the drum and means which upon movement of said frictional member with the drum will lock the second named clutch member in 110 frictional engagement with said drum, said loosely mounted collar having a cam surface for engagement with the said means which is carried by the friction member.

9. Land leveling and grading apparatus comprising a frame, an axle rotatable on the frame, wheels supporting said axle and rotatable freely thereon, a scoop associated with the axle and the frame, means for locking the wheels to and causing rotation of 115

the axle, means which when the axle rotates will move the scoop into scooping, load conveying and load dumping positions and means for controlling the operation of the 5 last named means.

10. Land leveling and grading apparatus comprising a frame, an axle rotatable on the frame, wheels supporting said axle and rotatable freely thereon, a scoop associated 10 with the axle and the frame, means for locking the wheels to and causing rotation of the axle, means which when the axle rotates will move the scoop into scooping, load conveying and load dumping positions, means 15 for controlling the operation of the last named means, draw bars connected with the forward portion of the scoop, a slide member on the frame forwardly of the scoop to which said draw bars are connected and 20 means which when the scoop is lowered into scooping position will lock said sliding member against movement and which when the scoop is raised from scooping position will release said sliding member.

25. 11. Land leveling and grading apparatus comprising a frame, wheels supporting the frame, an axle upon which the wheels are rotatable, a scoop mounted for movement relative to and with the axle, means including clutch mechanisms for locking the wheels to and causing rotation of the axle for moving the scoop into scooping, load conveying and load dumping positions, draw bars connected with the scoop, a slide member on the frame forward of the scoop and to which said draw bars are connected and means automatically locking the slide member against movement when the scoop is moved into scooping position and automatically releasing said slide member when the scoop is moved out of scooping position.

30. 12. Land leveling and grading apparatus comprising a frame, an axle rotatable on the frame, wheels supporting said axle and freely rotatable thereon, clutch means for locking said wheels to the axle and causing rotation of the axle upon turning the wheels, a scoop member, a rack bar carried by the scoop member extending upwardly therefrom, a pinion fixed to the axle and engaging with said rack bar, means arranged to permit movement of the rack bar relative to the pinion when the scoop is in elevated position clear of the ground and unloaded, which means automatically, after movement of the scoop when loaded into position free of the ground, will lock the rack bar against movement relative to and cause it to move with said pinion upon rotation of the axle whereby the scoop will be tilted out of a load supporting position.

35. 13. Land leveling and grading apparatus comprising a frame, wheels supporting the frame, an axle rotatable in the frame and upon which the wheels are loosely mounted,

clutch mechanisms for locking the wheels to and causing rotation of the axle, means for operating the clutch means, a scoop and means of operative connection between the scoop and axle provided for movement of 70 the scoop into scooping, load conveying and load dumping positions when the clutches are operated to cause rotation of the axle as the wheels are continuously moved.

14. Land leveling and grading apparatus 75 comprising a frame, wheels supporting the frame, a revolvable member on the frame, clutch means associated with the wheels and revolvable member for causing rotation of the revolvable member, a scoop mounted for 80 movement relative to and with the frame and means associated with the scoop and revolvable member for positively moving the scoop into scooping position on actuation of the clutch means and the subsequent 85 rotation of the revolvable member, which means provides for regulating the extent of movement of the scoop into scooping position by actuation of the clutch means.

15. Land leveling and grading apparatus 90 comprising a frame, wheels supporting the frame, a revolvable member on the frame, clutch means associated with the wheels and revolvable member for causing rotation of the revolvable member, a scoop mounted for 95 movement relative to and with the frame, means associated with the scoop and revolvable member for positively moving the scoop into scooping position on actuation of the clutch means and the subsequent rotation of the revolvable member, which means provides for regulating the extent of movement of the scoop into scooping position by actuation of the clutch means and spring means resisting movement of the 100 scoop into scooping position and acting automatically upon declutching of the clutch means following a scooping operation, to lift the loaded scoop into load conveying position.

16. A land leveling and grading apparatus comprising a frame, wheels supporting the frame, a revolvable member on the frame, clutch means associated with the revolvable member and wheels, which when in 115 operative position will cause said revolvable member to rotate, a scoop operatively associated with the frame and means associated with the revolvable member and scoop for forcing the scoop into scooping 120 position when the clutch means is actuated and said revolvable member is caused to revolve.

17. A land leveling and grading apparatus 125 comprising a frame, wheels supporting the frame, a revolvable member on the frame, clutch means associated with the revolvable member and wheels, which when in operative position will cause said revolvable member to rotate, a scoop operatively 130

- associated with the frame, means associated with the revolvable member and scoop for forcing the scoop into scooping position when the clutch means is actuated and said revolvable member is caused to revolve and means which when the scoop mechanism is declutched following a scooping operation will automatically lift the loaded scoop into load conveying position.
18. Land leveling and grading apparatus comprising a frame, wheels supporting the frame, a revolvable member on the frame, clutch means associated with the wheels and said member for causing rotation of said

member on rotation of said wheels, and a 15 scoop mounted on the frame so as to be movable into and out of scooping position.

19. Land leveling and grading apparatus comprising a frame, a scoop mounted on the frame for movement into and out of scoop- 20 ing position, means for holding the scoop in scooping position and means which on release of said holding means automatically lifts the loaded scoop into load conveying position.
